UNITED STATES PATENT OFFICE

ussell C. Taylor, Greenwich, Conn., assignor to American Can Company, New York, N. Y., a corporation of New Jersey.

Application September 16, 1939, Serial No. 295,307

1-6

Russell C. Taylor, Green
American Can Company
corporation of New York
Application September 1, 1937
1 Claim.
The present invention relates to containers for
packaging and delivery of liquids, such as milk,
fruit juices or the like and has particular reference
to a sanitary fibre container of a construction
wherein water or other undesirable sub-
stances coming in contact with the top of the
container are prevented from running into the
container. An attempt has been made to
The invention constitutes an improvement
upon the container illustrated and described in
the John M. Hothersall, United States Patent
2,085,979, issued July 6, 1937, and is especially
an improvement on the top closure construction
thereof.

taken substantially along a vertical plane indicated by lines 3-3 in Fig. 1.

The container illustrated in the drawing is a preferred embodiment of the invention. The drawing shows a container of the general construction described in detail in the patent hereinbefore mentioned. The container briefly comprises a substantially rectangular body 11 closed at its ends with suitable top and bottom closure members. The closure members are generally alike and for the purpose of the invention only the top closure member need be illustrated. This is broadly designated by the numeral 12.

The body 11 is preferably formed from a single sheet of fibrous material folded at right angles to provide four side walls designated by the numeral 13. The edges of the sheet are joined along one of the side walls by overlapping the short edges of the sheet to form a vertical lap 15 side seam 14 (Figs. 1 and 2). The seam edges are preferably secured with a suitable adhesive so that a liquid tight side seam results.

The end members, as exemplified by the top closure member 12, are preferably square and formed of fibrous material. Fig. 3 of the drawing shows in detail how the top closure member 12 is interlocked with the adjacent end or marginal portion of the body, the body marginal portions being bent inwardly as at 15 and thence outwardly as at 16 thereby providing a ledge 17 which extends circumferentially of the body upon which the closure member 12 is supported. The extreme edges of the body marginal portions are bent upwardly and thence inwardly over the outer edges of the closure member thus providing opposite end flanges 18 which hold the closure member in place.

The bent parts 16, 18 of the body adjacent its ends and the edges of the top closure member 12 are preferably secured with a suitable liquid proof adhesive. Thus far the description fits the Hothersall patented container referred to above. The liquid tight end seam thus provided is indicated by the numeral 19.

45 The top closure member 12 (Figs. 2 and 3) has a vertical or upstanding annular flange wall 21 defining a pouring opening 22 located adjacent one corner of the closure member. This wall or 50 annular collar imparts a spout effect for dispensing through the pouring opening and deflects and guides fluid contents issuing from the container so that such contents do not pour over and strike upon the outer surface of the closure member 12 or upon the flat flange 18. This produces a clean 55 and sanitary dispenser outlet.

Referring to the drawing:

Figure 1 is a fragmentary perspective view of the upper part of a container embodying the present invention and illustrating the top of the sealed container sealed by the closure member;

Fig. 2 is a view similar to Fig. 1 showing the hinged closure member in its opened position upon the container; and

Fig. 3 is a fragmentary enlarged sectional view

A hinged closure 23 is provided for closing the pouring opening 22. Should liquid or other substance come in contact with the closure member, whether the hinged closure is opened or closed, it would drain off and not run past the annular collar into the pouring opening with possible contamination of the container contents. The top of the annular wall is substantially at the same level or at least as high as the top of the flat flange 18.

The hinged closure member 23 (Fig. 2) is formed with a drawn plug section 24 which fits into and closes the pouring opening. To insure a more secure seal for a filled can this drawn plug section may be slightly altered in shape by a suitable expanding tool to form a circumferential bead 25, as illustrated in Fig. 3. This bead is thus formed from the material of the plug 24 and is pressed beneath the raised annular wall 21 to more effectively seal the auxiliary member in its closed position. The waxed or otherwise treated surface of the plug 24, frictionally engaging with the inner wall 21 of the opening 22, makes this a liquid tight closure.

The hinged closure member 23 is hingedly secured to the top closure member 12 by a wire staple 26 thereby permitting the closure member to be swung back, as illustrated in Fig. 2. This facilitates pouring out of the container contents. The closure element 23 where it surrounds the pouring end, rests tightly upon the flat flange 18 (Fig. 3) thereby protecting the covered parts from contamination and giving added protection against contamination of the contents of the container.

It is thought that the invention and many of

its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

- 10 A container comprising a tubular fibre body having an end portion thereof inclined inwardly and thence extended outwardly to provide a substantially flat end support ledge and thence extending upwardly and terminating in an inwardly extending peripheral flange of single thickness, a substantially flat end closure member having its peripheral portion engaging and supported by said ledge and enclosed within said body flange to constitute an end joint, said end closure member having a vertically disposed annular flange surrounding and defining a dispensing opening adjacent the margin of the container, said closure member flange constituting a spout wall having a vertical dimension at least equal to the thickness of said body flange to prevent undesirable contaminating foreign matter on the end closure member from flowing into the dispensing opening, and a closure element hingedly secured to said end closure member for closing the dispensing opening, the outer edge of said spout wall engaging beneath said hinged closure element and an outer portion of said element resting in substantially flat close contacting engagement with said inwardly extending terminal body flange, when the container is closed.
